F i g. 5

Figure 1 is a side elevational view of a combined truck and lift, showing my new design;

Figure 2, is a front elevational view thereof;

Figure 3 is a rear elevational view thereof;

Figure 4 is a top plan view thereof; and

Figure 5 is a side elevational view thereof opposite the side shown in Figure 1 with the roof corner removed and with the work basket in an elevated position.

The essential features of the design reside in the portions shown in solid lines.

I claim:

The ornamental design for a combined truck and lift, substantially as shown and described.
